TABLE FOR FOOD PRODUCTS DISPLAY

Franklin Moore, Jr., 902 McBurney Drive,
Lebanon, Ohio 45036

Filed Apr. 30, 1974, Ser. No. 465,537

Term of patent 14 years

Int. Cl. D20—02

U.S. Cl. D6—20

FIG-1

FIG-2

FIG-3

FIG-4

FIG-5

FIG-6

FIG. 1 is a perspective view of a table for food products display showing my new design.

FIG. 2 is a side elevational view thereof.

FIG. 3 is a top plan view thereof.

FIG. 4 is a perspective view showing a modification in the table for food products display of this invention.

FIG. 5 is a side elevational view of the table for food products display of FIG. 4.

FIG. 6 is a top plan view of the table for food products display of FIGS. 4 and 5.

I claim:

The new and ornamental design for a table for food products display, substantially as shown.
